UNITED STATES PATENT OFFICE.

WILLIAM SMITH, OF READING, PENNSYLVANIA.

DOOR-LATCH.

1,274,096.

Specification of Letters Patent. Patented July 30, 1918.

Application filed November 26, 1917. Serial No. 204,030.

To all whom it may concern:

Be it known that I, WILLIAM SMITH, a citizen of the United States, residing at Reading, in the county of Berks and State of Pennsylvania, have invented certain new and useful Improvements in Door-Latches, of which the following is a specification.

This invention relates to door latches and more particularly to an improved sliding latch adapted to be attached to a door and operated by a knob in a manner that will cause an operation of a latch regardless of the direction of rotation of the knob. One of the principal objects of the invention is to provide a sliding latch bolt adapted to be drawn into a casing carried by the door when the knob is turned in either direction and which will be arranged to move to operative locking position as soon as the knob has been released.

The invention further aims at the provision of a latch of this character that will be arranged within the casing and consist of a number of parts supported by the ends of the casing in a manner that will permit free sliding movement of the operative parts thus eliminating all unnecessary friction and causing a free movement to be imparted to the operating parts when the knob is actuated.

A further object of the invention is the provision of a device of this character which consists of comparatively few parts and is simple in construction but durable and well adapted to withstand the rough usage to which devices of this character are ordinarily subjected.

For a full description of the invention and the advantages and merits thereof, reference is to be had to the following description and the accompanying drawings wherein is illustrated the preferred form of my invention, in which:

Figure 1 is a longitudinal section through the latch showing the mechanism mounted therein.

Fig. 2 is a section taken on the line 2—2 of Fig. 1.

Fig. 3 is a section taken on the line 3—3 of Fig. 1.

Referring to the drawing wherein is illustrated the preferred form of my invention, in which like numerals of reference indicate corresponding parts throughout the several views, the casing 1 is of substantially rectangular formation and is adapted to be fit-

ted into a door in the usual manner and has the flange 2 at one end whereby the casing may be screwed or bolted to the door for holding the casing in fixed position. One side of the casing is provided with a removable plate 3, where access may be gained to the interior of the casing and this plate is attached through the medium of screws 4 received in lugs 5 carried by the casing at 65 points adjacent the edge of the open side.

The front or end wall of the casing is provided with an opening 6 through which the tongue 7 of a sliding bolt is projected and this bolt includes the curved arms 8 which are extended in spaced relation and have their terminals provided with lugs 9. Engageable with the lugs are the fingers 10 of a yoke member 11 which includes a spacing bar 12 the ends of which are connected to the fingers 10. Intermediate the ends of the bar 12 is a suitable opening 13 for receiving one end of a rod 14 which projects through an opening and has its end fastened to a pin 15. The opposite end of the rod is fixed in any suitable manner to the end wall of the casing and a coil expansion spring 16 encircles the rod and is interposed between the end wall of the casing and the edge of the bar 12 for normally urging the 85 ends of the fingers 10 into engagement with the lugs 9 whereby the tongue 7 will be normally projected through the opening 6. In this manner the tongue may be held in the ordinary socket ordinarily employed with 90 latches and which are usually mounted on the door jamb. In order that the sliding bolt may be operated I have provided an operating rod or stud shaft 17 which projects through a suitable opening in the side of the casing and has its inner end reduced in size to form a square extension 18 received in a correspondingly shaped opening 19 and an actuating lever 20. This lever includes oppositely extending arms the terminals of which are in engagement with the spaces of the lugs opposite to the faces engaged by the ends of the fingers 10. The opposite or other end of the stud shaft 17 is provided with a suitable knob 21. To 100 operate the latch it is merely necessary to turn the knob and either one of the arms will force the corresponding lug inwardly against the pressure exerted by the spring 16 so that the tongue 7 will be drawn into 110 the casing and thus be released from the socket in the door jamb. It is to be observed

that this action will occur regardless of the direction of rotation of the knob. Since the rod 14 is rigidly fixed to one end of the casing and has its opposite end projected 5 through the opening in the bar 12, the bar is thereby slidably supported without contact with the casing and since the substantially square tongue 7 is slidably mounted in the opening 6 in the said end wall of the 10 casing, this tongue will also be slidably mounted without any other portion of the bolt contacting with the casing. Thus the two parts are slidably mounted in a manner that will prevent any excessive friction and 15 consequently cause an ease of operation when the knob is turned that has not been heretofore obtained in devices of this character.

In order that the actuating lever may turn 20 in the exact center of the casing, that is in the same plane as the rod 14, I have provided recesses in the arms of the yoke. These recesses or depressions indicated at 21, provide a space for receiving the actuating 25 lever 20 and the lugs 9 are extended at right angles so that they are in the path of movement of the arms of the actuating lever.

From the foregoing it will be observed 30 that a very simple and durable latch has been provided the details of which embody the preferred form. I desire it to be understood, however, that slight changes in the minor details of construction may be made without departing from the spirit of the invention or the scope of the claims hereunto appended.

I claim:

1. A door latch comprising a casing having a sliding bolt mounted therein, curved 40 arms formed on the bolt and having their terminals disposed in spaced relation and provided with right angularly disposed lugs, a yoke member comprising a spacing bar having fingers formed at the ends 45 thereof engageable with the said ends of the curved arm, a rod fixed to one end of the casing and projecting centrally there-

through and slidably supporting the said spacing bar, resilient means interposed between the end of the casing and the said spacing bar, for urging the said fingers into engagement with the terminals of the arm, and actuating levers rotatably mounted within the casing and provided with oppositely extending arms engageable with the 55 said lugs on the faces thereof opposite to the faces engaged by the ends of the said fingers.

2. A door latch comprising a casing having a sliding bolt mounted therein, curved 60 arms formed on the bolt and having their terminals disposed in spaced relation and provided with right angularly disposed lugs, a yoke member comprising a spacing bar having fingers formed at the ends 65 thereof engageable with the said ends of the curved arm, a rod fixed to one end of the casing and projecting centrally there-through and slidably supporting the said spacing bar, resilient means interposed between the end of the casing and the said spacing bar for urging the said fingers into engagement with the terminals of the arm, and actuating levers rotatably mounted 70 within the casing and provided with oppositely extending arms engageable with the said lugs on the faces thereof opposite to the faces engaged by the ends of the said fingers, the said yoke and curved arms being centrally mounted in the casing the said 75 arms having depressions for providing a central space to receive the central actuating lever, the said arms of the actuating lever being movable in the said depression for engagement with the said lug to move 80 the said locking bolt centrally against the pressure of the fingers exerted by the said spring.

In testimony whereof I affix my signature in presence of two witnesses.

WILLIAM SMITH.
